[57] CLAIM

The ornamental design for a toy, as shown and described.

DESCRIPTION

FIG. 1 is a perspective view of a first embodiment of a toy showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and

FIG. 7 is a rear elevational view thereof.

FIG. 8 is a perspective view of a second embodiment of a toy showing our new design;

FIG. 9 is a top plan view thereof;

FIG. 10 is a bottom plan view thereof;

FIG. 11 is a left side elevational view thereof;

FIG. 12 is a right side elevational view thereof;

FIG. 13 is a front elevational view thereof; and,

FIG. 14 is a rear elevational view thereof.

FIG. 15 is a reference perspective view of the first embodiment, wherein the toy is in a using position; and,

FIG. 16 is a reference perspective view of the second embodiment wherein the toy is in a using position.

The broken line showing of the toy in FIGS. 15 and 16 is for illustrative purposes only and forms no part of claimed design.
